UNITED STATES PATENT OFFICE

EDWARD W. STRUBE, OF BRIGHTWATERS, NEW YORK

INCINERATOR

Application Filed December 13, 1929. Serial No. 413,754.

This invention relates to an incinerator and particularly to an incinerator having means for the burning of waste material and the simultaneous heating of a liquid element such as water, or the like.

A further object is to provide means for directing the flame of an auxiliary fuel such as gas, oil or the like in such a way that the heat thereof is applied to liquid containing elements and at the same time is brought into contact with waste material in the fire chamber of the incinerator.

Another object is a form of construction for the support of the liquid container members and for the shielding and protection of the said members against jagged or weighty objects which may be present in the mass of the waste material.

A further object is to provide for economy in the use of fuel for the burner element. This economy being effected by the placement of the water coil within the fire chamber where it may be heated directly by the burning of the waste material and without the use of the burner flame when there is sufficient material in the chamber for the purpose; the burner flame being available when the heat dies down in the fire chamber; the two means of heating being usable in combination with each other when the waste material is of such a nature as to be slow burning or hard to ignite.

Another object is to provide a means for agitating and loosening up the waste material in order to permit of a better oxygen distribution through the same while burning and to permit the flame from the auxiliary burner to enter the mass.

These and other objects and features of the invention will be fully set forth and described in the following specification and claims, and illustrated in the accompanying drawings, in which:

Fig. 1 is a front view of the incinerator with a portion cut away to show the water coil in section.

Fig. 2 is a side view of the upper portion of the incinerator in which the water heating elements are located.

Fig. 3 is an approximate half section on the

line 3—3 of Figure 2 and shows a top view of the water coil, and the grate and lower members of the incinerator.

Referring mainly to Figure 1 of the drawings; the incinerator is constructed as follows:

A casing 10 which may be cylindrical in form or of any desired shape, has an inner lining 11 and an air space 12 for the purpose of lowering the heat adjacent to the outer wall. A fire chamber 13 is supported within the casing and in such a way as to leave an intervening air space 14 between it and the lining 11.

The fire chamber is sustained partly by the bolts 15 on three sides of the casing and in part by the sleeves 16 on the fourth side thereof, which sleeves engage the chamber wall at their inner ends and are secured outwardly by the nuts 17. The fire chamber wall is perforated as seen at 18. At the bottom of the fire, or combustion chamber 13, the grate 19 is located and supported on the brackets 20. The grate is provided with suitable means for dumping and the like. The door 21 gives access to the ash pit, and the draft shutter 22 provides means supplying air to the combustion chamber.

The auxiliary burner 24 projects out through the wall casing and has a shut off valve 25. A pilot light 26 is located under the burner and has a valve 27. The auxiliary fuel supply pipe is seen at 28. A plate 29 is positioned behind the valve elements and a guide pulley 30 is mounted thereon. A chain 31 is connected to the valve levers and springs 32 retract the said levers. The chain may be extended to any desired point and a pull ring attached, or it may be connected with a thermostat if it is desired to control the fuel supply in relation to the operating requirements.

A door 33 gives access to the pilot light, and a shield 37 located over the coil outlet protects the said light from possible extinguishment by falling particles of waste material when such is being put into the incinerator.

The water coil 34 is located at the side of the fire chamber and has an intake end 100

35 and an outlet end 36 thrust through the wall of the fire chamber and outward through the sleeves 16 to the exterior of the incinerator where they may be connected as required.

5 The coil is retained and protected in its position adjacent the fire chamber wall by two sheathing elements 39 and 40 which pass around its sides and are secured to the wall 10 of the chamber by means of outbent edges seen in Figure 3 at 41. These edges engage the groove members 42 which are secured to the fire chamber wall and extend vertically thereon along the sides of the coil chamber. 15 Returning the description to Figure 1; it will be seen that the element 40 which is the lower of the sheath members, is perforated as seen at 44. These perforations permit the flame from the auxiliary burner to flare out 20 at the sides and come into contact with such material as is in the fire chamber; the flames thus pass between the pipe coils as well as along their inner sides.

The upper element 39 of the sheath members which rests on the top of the member 40 25 coming in contact therewith at the point 43, has no perforations and it thus serves to keep any waste material from lodging below or about the burner nozzle and shutting off the 30 flame from the said burner, or the pilot light. It will be observed that the flame from the 35 said pilot light shoots across to the edge of the burner through the hole 45 in the fire chamber wall.

35 A cover plate 46 rests upon the top of the element 39 and effects a closure over the coil chamber. This cover plate is secured at 40 to the chamber wall and is inclined downward toward the center of the said chamber 45 and thus prevents the lodgement of any waste material thereon.

As the waste material, garbage and the like in the fire chamber is apt to become matted and dense and thus hard to burn; an agitator bar 50 is provided to operate co-ordinately 45 with the auxiliary burner flame, and by thus agitating, the said waste material may be separated and moved about to permit of the 50 flames which shoot out of the sides of the coil chamber to enter the mass; and at the same time the oxygen supply to the burning material is increased by this movement. This bar, which is seen best in Figure 2 has a cross pin 52 which is adapted to engage the plate 55 58 and thus acts as a stop element. An elongated slot 54 in the wall of the fire chamber permits of a vertical swing of the bar and of forward and backward thrusts of the same, but prevents any side motion thereof. It is

60 desirable to prevent any side play of this member as it might, if brought into violent contact with the coil sheathing while the same was red hot, caused injury to the pipe coil. Normally, the bar is withdrawn from 65 the fire chamber and hung conveniently near

to the incinerator. A cover tab 55 closes the slot when the bar is removed.

Material is put into the incinerator through the chute 58 and this is covered by the lid 59. An elliptical smoke pipe 60 provides 70 means for connection with a suitable chimney.

While the invention is shown and described in its preferred form, it is understood that it is not limited narrowly to the exact details of 75 form and construction as herein described, but it is to be broadly construed within the scope of the appended claims.

Having thus described my invention, what I claim as new and desire to secure by Letters Patent, is as follows:

1. In an incinerator, an outer casing, a fire chamber within the said casing, a water coil within the said chamber and having inlet and outlet connections with the exterior of the 85 casing, an auxiliary fuel burner inserted within the said coil and downwardly directed and adapted to direct its flame along the interior of the coil contour, a sheathing about the upper portion of the said coil and a cover 90 element which shuts off the area adjacent the nozzle of the said burner from the fire chamber, and a lower sheathing about the said coil, which sheathing is provided with openings adapted to allow the passage of the auxiliary burner flame from the inner area of the coil to the interior of the said fire chamber.

2. An incinerator of the class described comprising, an outer casing, an interior fire chamber, a water coil placed within the said chamber and having inlet and outlet connections, the said coil being parted at one side for the passage of an auxiliary burner which is downwardly directed, and the said coil 100 wound below the said burner in a series of turns which are separated from each other and permit of the passage of a portion of the flame from the said burner to the fire chamber, means to ensheathe the said water coil 105 and means for the passage of flames from the said auxiliary burner through the said sheathing.

3. In an incinerator, an outer casing, a fire chamber within the said casing, a water coil 115 supported vertically within the said fire chamber and the said coil having its lower convolutions spread apart, and its upper coils widely parted at the back for the passage of an auxiliary burner between the same, the said burner being downwardly directed within the coil convolutions, a close walled sheathing about the upper portion of the said coil and a perforated sheathing about the lower portion thereof, an inclined cover plate over the said coil and sheathing, and inlet and outlet extremities of the said coil passing through the outer casing and inclosed within sleeve members which also act as partial supports for the fire chamber.

4. In an incinerator having a fire chamber consisting of a perforated wall set in spaced relation to an outer casing, a water coil set within the said fire chamber and at one side thereof, and the said coil encased around its upper portion with a closed sheathing, and around its lower portions with a perforated sheathing, and a cover element over the top of the said closed sheathing, and an auxiliary burner inserted within the contours of the said coil and set to direct its flames in a downward course within the convolutions of the said coil.

Signed at New York city in the county of New York and State of New York this 3rd day of December A. D. 1929.

EDWARD W. STRUBE.
